UNITED STATES PATENT OFFICE.

WALTER McC. FERRIER, OF CARNEGIE, PENNSYLVANIA.

GAS-BURNER.

1,177,027.

Specification of Letters Patent. Patented Mar. 28, 1916.

Application filed November 28, 1914. Serial No. 874,438.

To all whom it may concern:

Be it known that I, WALTER McC. FERRIER, a citizen of the United States, residing at Carnegie, in the county of Allegheny and State of Pennsylvania, have invented new and useful Improvements in Gas-Burners, of which the following is a specification.

This invention relates to gas burners and has for its particular object the provision of means whereby a more perfect mixing of the air and gas is obtained.

With this and other objects in view, as will be hereinafter brought out, reference will be had to the accompanying drawings forming a part of this specification and wherein like characters of reference designate corresponding parts throughout the several views, in which:

Figure 1 is a longitudinal sectional view 20 of the invention, Fig. 2 is a similar view of one section of the mixing tube, Fig. 3 is an end elevation of Fig. 2, Fig. 4 is a transverse sectional view taken on line 4—4 of Fig. 2, Fig. 5 is a transverse sectional view taken 25 on line 5—5 of Fig. 2, Fig. 6 is a view similar to Fig. 1, of a modified form, Fig. 7 is a view in elevation of one end of the secondary nozzle, Fig. 8 is a longitudinal sectional view of the secondary nozzle and a fragment of one section of the mixing tube, and Fig. 9 is a longitudinal sectional view 30 through one of the screen spacers.

Referring to the drawings, reference character 1 designates the burner tube and 35 may be the burner tube itself or a lead pipe thereto. This tube is threaded in a pipe 2 constituting one section of the mixer tube, the other sections being designated by characters 3 and 4. These sections 2, 3 and 4 are 40 secured together into a unitary member by means of flanges 5 and bolts 6, and by similar means, the air supply elbow pipe 7 is joined to the section 4. To the elbow 7 is threaded a pipe 8 supplying air under pressure 45 from a blower or other pumping or forcing device, not shown. A gas supply pipe 9, from the gas line or main, is threaded into the mixer tube section 4 and its axis bears a right angular relation to the axis of 50 the mixer tube.

Between the flanges 5 of the elbow 7 and the mixer section 4 is clamped the peripheral flange 10 of the tubular air nozzle 11, which will be referred to as the primary air 55 supply nozzle. The tubular portion of this nozzle is entirely open at both ends and its

outer wall is spaced from the inner wall portion of the mixer section 4, and into the space 12 so formed, air from the primary nozzle 11 enters in radial jets through ports 14 provided in the sides of the primary nozzle 11. These ports 14 and the inner end of the said nozzle 11 are substantially within the plane of the gas inlet 9 so that the entering gas is divided and its divisions deflected 65 into paths on opposite sides of the primary nozzle 1 and each division is sprayed with the air issuing from the jets 14.

Between the flanges 5 of the mixer sections 3 and 4 is clamped the peripheral flange 15 of a secondary nozzle 16, this nozzle being tubular and having one end entirely open and its opposite end partially closed by an end flange 17, presenting only a small opening 18. The sides of this tubular nozzle 16 are provided with longitudinal 70 slots 19 through which the mixture, with air predominating, issues in radial jets to break up and mingle with the mixture, with gas predominating, that passes between the 75 tubular secondary nozzle 16 and the wall of the mixer section 3. The flange 15, it will be noted, is provided with openings 20 affording passage-ways for the mixture and arms 21 to support the secondary nozzle 16 80 concentrically within the mixer section 3.

The admission end of the bore of the mixer section 3 is flared as at 22 and this flared portion is provided with baffle sections 24 which extend partially onto the unflared portion of the bore. With each of the baffle sections 24 aline helically two other baffle sections 25, 26 so as to present three sets of helical baffles, each composed of helical baffle sections 24, 25 and 26. The 95 baffle sections 24, in addition to being applied locally to the flared portion of the bore of the mixer section 3, extend from the inner wall of said section to points intimately adjacent the outer surface of the secondary nozzle 16, so that all of the mixture entering mixer section 3 through the openings 20 is given a twirling motion prior to being subjected to the radial jets issuing from the ports 19 of the secondary nozzle. 100

After being broken up by these last mentioned radial jets, the mixture is again given a twirling motion by the baffle sections 25 and later by the terminal baffle sections 26. As the twirling mixture leaves the ends of 110 the various baffle sections, it endeavors to straighten out its line of movement, par-

tially prompted by the jet issuing from the port or opening 18 in the end of the secondary nozzle, and hence, each baffle section acts upon a different portion of the body 5 of the mixture than its immediately preceding one of its helical series.

It will be observed that the diameter of the primary nozzle 11, or its discharge opening, at its end, is greater than the diameter 10 of the secondary nozzle, and this is responsible to cause a portion of the air, with its surrounding and partially mingled body of gas to enter the openings 20 and be subjected to the twirling effect of the baffles. The 15 remainder of the air from the primary nozzle, or its axial portion, enters the interior of the secondary nozzle and issues from the ports 19 thereof and a small portion from the end opening 18 of said secondary nozzle. 20 Of course, it is not possible to authoritatively delineate the exact path taken by each particle of air and gas, but the foregoing is substantially a correct portrayal of the general scheme of flow. It is known, 25 however, that the combination of the two nozzles 11 and 16 and the baffles produces an excellent mixture of the air and gas. This mixture is made more perfect by its passage through screens 30, which may be of 30 the same or of different gage and located within the section 2 and spaced apart by gaskets 31, the bores of which taper inwardly toward their discharge ends to act as funnels to concentrate or converge the minute currents in their highly agitated and 35 turbulent state coming from the baffles of the mixer section 3. These gaskets 31, it will be noted, concentrate the mixture to act upon the small current of the mixture, mostly air, 40 issuing from the port 18 to completely absorb the same.

With this invention, it will be observed

that at all times there is a positive propelling force in the current which travels locally along the axis of the mixer tube, first 45 from the air pipe or primary nozzle and then from the opening 18 in the secondary nozzle, which axial current, as stated, is finally merged into the more perfect mixture produced by the baffles and radial jets from 50 the ports 14 and 19.

The modified form of Fig. 6 is substantially identical with the preferred form, except that between the air supply elbow 7 and the mixer section 4 is an adjustable 55 nipple constituting the primary air supply nozzle 11' in lieu of the non-adjustable nozzle 11 of Fig. 1.

What is claimed:

A gas burner, comprising a burner tube 60 and a mixing tube, open end primary and secondary nozzles alined with each other concentrically within and spaced from the walls of the mixing tube, said nozzles having side openings, means for supplying air to the primary nozzle from which it passes to the secondary nozzle, means for supplying gas to the space between the primary nozzle and the mixing tube, helical series 65 of baffles each composed of separated baffle sections located on the inner wall of the mixing tube and extending into the space between the secondary nozzle and the mixing tube, and a plurality of spaced screens 70 between the burner and mixing tubes, said 75 screens being separated by gaskets having funnel-shaped openings.

In testimony whereof I have hereunto set my hand in presence of two subscribing witnesses.

WALTER McC. FERRIER.
